BOBBIN TIP SUPPORT MEANS FOR WEFT REPLENISHING LOOMS

Richard G. Turner, Worcester, Mass., assignor to Crompton & Knowles Loom Works, Worcester, Mass., a corporation of Massachusetts

Application July 28, 1948, Serial No. 41,037

7 Claims. (Cl. 139—247)

1

This invention relates to improvements in weft replenishing looms and it is the general object of the invention to provide improved support means for the bobbin tips of reserve bobbins constructed in such manner as to avoid abrasion of the weft ends of the bobbin during weft replenishing operations.

In weft replenishing looms more particularly of the multicolor type it is customary for bobbins to move down guideways by gravity toward transfer position. The weft ends of the bobbins lead to some form of thread holder and are likely to be pinched between the bobbin tip and the support means for the latter when the bobbin is being pushed out of the reserve bobbin magazine into a depleted shuttle. When particularly fine yarns are used the abrasion may be sufficient to cause breakage with resultant non-threading of the shuttle and loom stoppage.

It is an important object of the present invention to provide roll means for supporting both sides of a bobbin tip and mount one of the roll means so that it can move away from the other to permit passage between them of the bobbin tip.

It is a further object of the invention to provide a roll made of deformable material softer than the bobbin tip into which the fine weft thread can be embedded without serious damage thereto as the bobbin moves between its supports.

In weft replenishing mechanisms of the type to which the invention more particularly relates it is frequently desirable to use either right hand or left hand wound bobbins in either of the stacks of reserve bobbins. As heretofore made the yielding bobbin support of a given stack has been favorable for use of one or the other of these winds, but not both. It is a further object of the invention to provide the magazine with a supporting roll for each side of a bobbin tip so that either right or left hand wound bobbins can be used in either stack.

With these and other objects in view, which will appear as the description proceeds, the invention resides in the combination and arrangement of parts hereinafter described.

In the accompanying drawings, wherein a convenient embodiment of the invention is set forth,

Fig. 1 is a front elevation of a weft replenishing mechanism having the present invention applied thereto, parts being in cross section,

Fig. 2 is an enlarged elevation of the outer plate of the magazine looking in the direction of arrow 2, Fig. 1, and showing the bobbin tips and part of the magazine in cross section,

2

Fig. 3 is an enlarged horizontal section on line 3—3, Fig. 2.

Fig. 4 is an enlarged vertical section on line 4—4, Fig. 3, showing one of the pairs of bobbin supporting rolls, and

Fig. 5 is an enlarged plan view looking in the direction of arrow 5, Fig. 2.

Referring to the drawings, the reserve bobbin magazine M may be supported by means of a stationary pivot stud 10 and has inner and outer end plates 11 and 12, respectively. The magazine will support two groups or stacks of reserve bobbins which feed by gravity to transfer positions. The inner plate has provision for guiding the butts 13 of the reserve bobbins in the magazine, only one bobbin B with its weft W being shown in Fig. 1. The magazine rocks about the stud 10 by mechanism not shown herein but well understood so that the lowest bobbin in each stack can be in transfer position under a transferrer arm 14.

The outer plate 12 of the magazine is supported by tie rods 15 deriving their support from the inner plate 11. The outer plate comprises a flat wall 16 from which project four flanges to define two guideways for the tips of the bobbins. Two of these flanges, 17 and 18, are spaced to define a groove 19 for the tips of the front stack of bobbins, while the other two spaced flanges 20 and 21 define a groove or guideway 22 for the tips of the rear stack of bobbins.

The front of the plate 12 is provided with a guide wire 25 which extends downwardly at an angle to the plate as shown in Fig. 1 and has a lower thread guiding end 26 which is bent upwardly and then inserted into the web 16. In similar manner, a rear wire 27 has its lower yarn guiding end 28 bent upwardly and inserted into web 16. The latter is provided along the bottom thereof with a smooth weft engaging edge 30.

Plate 16 supports a pivot stud 35 on which is mounted for angular movement front and back bobbin tip supports 36 and 37, respectively. Support 36 has its upper end provided with a stop screw 38 held against flange 20 by a small tension spring 39 the upper end of which is held by a clip 40 stationary on the magazine. In similar manner, the upper end of the rear bobbin support 37, is provided with a stop screw 41 held against flange 18 by a light tension spring 42 connected to a second clip 43.

Except for the bottom ends of the guideway forming flanges 17 and 21, and the lower parts of the bobbin supports 36 and 37, the matter thus far described may be of common construction and operate in the usual manner.

In carrying the invention into effect provision is made for permitting the lowest bobbin tip of each stack of bobbins to rest on two rolls one of which preferably has its axis fixed with respect to the magazine and the other of which is rotatably mounted on a bobbin support.

Referring particularly to Fig. 3, the front bobbin support 36 carries a stud 50 on which is rotatably mounted a roll 51 made preferably of a compressible material softer than the tip of the bobbin, such as hard pressed felt. Web 16 has secured thereto a stud 52 on which is rotatably mounted a roll 53 similar to roll 51. A sleeve 54 between the web 16 and the roll 53 keeps the latter spaced from the web and in substantial alignment with roll 51. The tip of the bottom front bobbin is shown in section at 55 and rests on the rolls 51 and 53. The rear support 37 carries a stud 60 which supports a roll 61 for rotation, and stud 62 secured to the web 16 has rotatable thereon a fourth roll 63 spaced from the web 16 by a sleeve or collar 64. The tip 68 of the rear bottom bobbin rests on rolls 61 and 63.

The rolls 51, 53, 61 and 63 are preferably all alike and of the same size and made of a compressible material softer than the tips of the bobbins, such as rubber or fibrous pressed felt. Each roll has a bore 65 to receive the corresponding stud, and this bore is hardened by having the felt or similar fibrous material impregnated by some material, such as a plastic, which will provide a relatively hard inner shell 66 to serve as a bearing for engagement with the corresponding stud. The shell 66 is confined to the central parts of the roll and do not extend to the bobbin engaging periphery 67 of the roll. The rolls are arranged in pairs, rolls 51 and 53 being the front pair for the front stack or guideways 19, while the other rolls 61 and 63 form the rear pair for guideway 22. One roll of each pair rotates about a fixed axis and the other roll of each pair is mounted on a bobbin support capable of yielding against spring action, as will be apparent from Fig. 2. The lower ends of the outside flanges 17 and 21 are somewhat shorter than in previous reserve bobbin magazines of the general type shown herein in order to make room for the front and back rolls 53 and 63.

When reserve bobbins are placed in the magazine their weft ends are drawn off to the right of plate 12 as viewed in Fig. 1 and attached to some form of thread holder which is not shown herein. This thread holder may hold the weft ends taut so that they extend from their bobbins around their respective wires 25 and 27 and then outwardly away from the magazine toward the right, Fig. 1. As the bobbins descend in their stacks and approach their respective transfer positions the weft ends may become slack enough to slip off the lower ends 26 and 28 of the guide wires 25 and 27, in which event the weft ends will extend from the bobbin tips down along one or the other of the associated supporting rolls, and around smooth edge 30 toward the thread holder. A thread thus dislodged from its normal position and out of control of the corresponding guide wire may during transfer engage one or the other of the bobbin tip supporting rolls. Thus, referring to Figs. 2 and 3, if the weft end of the bobbin tip 55 should become dislodged from guide wire 25 it will extend down between tip 55 and one or the other of the rolls 51 or 53, and then around the guide edge 30. At transfer this thread may be subjected to some pressure, and if it is it will be embedded into one of the rolls supporting tip 55.

and not be abraded or subjected to any crushing action which would otherwise weaken it. Similarly, a weft end extending from the bottom tip 68 may extend along one or the other of the rolls of the rear pair and be embedded into it without being damaged.

In the past I have proposed that rolls be mounted on the bottoms of the support arms for the bobbin tips, such as those shown herein at 36 and 37, but such rolls were metallic and were harder than the bobbin tips and although they rolled or turned on their axes to prevent a scraping or abrading action on the yarn the latter nevertheless was subjected to some compression. Such rolls were shown for instance in my prior Patent No. 2,354,285.

When rolls are used on the bobbin supports only some difficulty may arise due to the direction of wind of the weft on the bobbins. If, for instance, the bottom front bobbin is wound in such manner that its weft end F leads downwardly from the left side of the tip 55 it will then engage roll 51 and be spared any appreciable deterioration growing out of transfer of the bobbin. If, on the other hand, the weft is oppositely wound it will lead down between the bobbin tip and the roll 53 and will similarly be spared any damaging compression or distortion of its filaments. As set forth in my prior patent a bobbin wound in the manner last described would be required to move along the flange 11, but as set forth herein this flange has been shortened to make room for roll 53. The bottom bobbin of the front stack can therefore be wound either right hand or left hand and its weft will be equally protected by one or the other of the rolls of the front pair. These same conditions also apply for the bottom bobbin of the rear stack regardless of the direction of wind of its weft.

It will thus be seen that by providing a pair of rolls, one for each side of the bobbin tip, the bobbin can be wound either right or left hand, and this is true for the bobbins of both stacks.

From the foregoing it will be seen that the invention sets forth simple means by which delicate weft yarns may be protected during a bobbin transferring operation, the means comprising a pair of rolls for each bobbin tip, each roll being free to rotate on its axis in response to frictional contact with the bobbin tip, and being preferably so constructed that the weft yarn can be embedded into it if it is caught between the bobbin tip and the roll. It will also be seen that the magazine can operate with bobbins of either right hand or left hand wind, in either the front or the back stack, this condition being due to the fact that each side of the lowest bobbin tip in each of the stacks rests on the rolling surface. The extreme front and back rolls 53 and 63 are so placed that a bobbin approaches them along the corresponding guideway and moves to transfer position without material disturbance or excess movement, as will be apparent from Fig. 2. While two rolls have been provided for each bobbin tip in transfer position, the invention is not necessarily limited to this arrangement, since the relatively soft compressible rolls 51 and 61 on the bobbin supports 36 and 37, respectively, have advantages independent of the rolls 53 and 63; these advantages growing out of the fact that the rolls on the supports are made of a compressible fibrous material soft enough to have delicate yarns embedded into them by a bobbin tip during a replenishing

operation. Also, the rolls may if desired have their bores 65 hardened by treatment with or application of an appropriate material, such as a plastic, applied either in fluid form and drying later, or applied by heat. In either event the roll has an inner shell which resists wearing when turning on its associated stud, but this shell does not extend to the periphery of the roll and the latter remains soft and possessed of the advantages already mentioned.

Having thus described the invention it will be seen that changes and modifications of the foregoing specific disclosure may be made without departing from the spirit and scope of the invention.

What is claimed as new is:

1. In a weft replenishing mechanism provided with a stack of bobbins which move down a guideway by gravity toward transfer position, a resiliently mounted bobbin tip support, a roll rotatably mounted on said support near the bottom of said guideway, and a second roll spaced from the first roll and rotatably mounted on the mechanism near the bottom of said guideway, the tip of the bottom bobbin of the stack resting on said rolls, the weft end of the bottom bobbin passing between said tip and one or the other of said rolls, and the latter being rotated by said tip at the time of bobbin transfer to prevent abrasion of said weft end.

2. In a weft replenishing mechanism having a stack of bobbins which move by gravity down a guideway toward transfer position, a pair of rolls located at the lower end of the guideway, means mounting one of said rolls for rotation about an axis fixed with respect to the mechanism, and a resiliently mounted bobbin tip support pivoted with respect to the mechanism and having the other roll rotatably mounted thereon, said rolls supporting the tip of the lowest bobbin in the stack and the weft end of the bobbin, depending upon the direction of wind of the weft on the bobbin, passing between said tip and one or the other of said rolls, said rolls being rotated by a bobbin being transferred to prevent abrasion of the weft end regardless of which roll engages said weft end.

3. In a weft replenishing mechanism having a stack of bobbins which move down a guideway by gravity toward a transfer position, a roll rotatably mounted on the mechanism near the bottom of said guideway for engagement with one side of the tip of the lowest bobbin in the stack, a second roll near the bottom of said guideway located for engagement with the other side of the tip of the lowest bobbin in the stack, the weft end of the bobbin engaging one or the other of said rolls, depending upon the direction in which the weft is wound on the bobbin, and a resiliently mounted support for the second roll, said rolls normally supporting the bobbin but said second roll due to the resilient mounting thereof moving away from the first roll when the bobbin is transferred and said rolls rotating to prevent abrasion of the weft end.

4. In a weft replenishing mechanism provided with a stack of bobbins which move down a guideway by gravity to a transfer position, a pair of

rolls located at the bottom of the guideway, each roll being made of fibrous material softer than the tip of the lowest bobbin in the stack, means mounting one of said rolls for rotation about an axis fixed with respect to the mechanism, and resiliently mounted means on which the other roll is rotatably supported, said resilient means normally holding said other roll stationary relatively to said one roll but being movable in a direction 10 away from said one roll, said rolls normally positioned to support the tip of the lowest bobbin in the stack and the weft end of said lowest bobbin passing between the tip thereof and one of said rolls, said bobbin when transferred causing rotation of said rolls and embedment of said weft end into the roll engaging the same to prevent abrasion of the weft end.

5. In a weft replenishing mechanism having a stack of bobbins which move down a guideway by gravity toward a transfer position, a pair of spaced rolls located at the bottom of the guideway and positioned normally to support the tip of the lowest bobbin in the stack, one of said rolls being rotatably mounted with respect to the mechanism and engaging one side of said tip, and resiliently mounted support means on the mechanism supporting the other roll for rotation thereon and holding said other roll in position to engage the other side of said tip, said rolls being 20 made of pressed felt softer than the said tip, the weft end of the lowest bobbin in the stack passing between said tip and one of said rolls, depending upon the direction of wind of weft on the bobbin, and being embedded into the roll engaged therewith to prevent abrasion of the weft end when the lowest bobbin in the stack is transferred.

6. A bobbin tip support for a weft replenishing mechanism, said support having provision for pivotal mounting on the mechanism and having a stud thereon on which is rotatably mounted a bobbin engaging roll made of a fibrous compressible material, said roll having a bore the surface of which is impregnated with a material harder than the roll and forming a shell to engage the stud but spaced from the periphery of the roll.

7. A bobbin tip support for a weft replenishing mechanism, said support having provision for pivotal mounting on the mechanism and having a stud thereon on which is rotatably mounted a bobbin engaging roll made of a hard pressed fibrous compressible material, said roll having a bore the surface of which is impregnated with a plastic compound harder than the roll to provide a bearing for engagement with said stud, said material forming a shell which is spaced from the bobbin engaging periphery of the roll.
